Fig. 11.

Fig. 12.

FIG. 1 is a side-elevational view of a boat fender, embodying my new design wherein the external line extends across the ends of the boat fender;

FIG. 2 is a side-elevational view of the boat fender shown in FIG. 1 rotated 90° from the position shown in FIG. 1;

FIG. 3 is an end view of the boat fender shown in FIG. 1 looking from either end;

FIG. 4 is a cross-sectional view taken along line 4—4 of FIG. 1;

FIG. 5 is a side-elevational view of a modified form of the boat fender shown in FIG. 1 wherein the lines pass into the ends of the boat-fender through the centers thereof;

FIG. 6 is a side-elevational view of the boat fender of FIG. 5, rotated 90° from the position shown in FIG. 5;

FIG. 7 is an end view of the boat fender shown in FIG. 5 looking from either end;

FIG. 8 is a cross-sectional view taken along line 8—8 of FIG. 5;

FIG. 9 is a side-elevational view of a further modified form of the boat fender wherein the external line extends across the ends of the boat fender through projecting ears;

FIG. 10 is a side-elevational view of the boat fender shown in FIG. 9 rotated 90° from the position shown in FIG. 9;

FIG. 11 is an end view of the boat fender shown in FIG. 9 looking from either end; and

FIG. 12 is a cross-sectional view taken along line 12—12 of FIG. 9.

The characteristic features of my design reside in an elongated cylindrical fender having spherically-shaped end portions and lines extending along the outside cylindrical surface of the fender parallel to the central axis thereof and substantially across the end portions thereof, the lines extending along the outside cylindrical surface being spaced 180° from one another as shown.

I claim:

The ornamental design for a boat fender, as shown and described.
